VERTICAL RISING AIRSHIP

Filed Nov. 8, 1927

FIG. 3.

Inventor:

J. D. Langdon
By Monroe Miller
Attorney.

UNITED STATES PATENT OFFICE

JESSE D. LANGDON, OF LOS ANGELES, CALIFORNIA

VERTICAL-RISING AIRSHIP

Application filed November 8, 1927. Serial No. 231,916.

The present invention relates to airships and aims to provide an airship which may rise or ascend vertically similar to a helicopter, and which may have flight similar to an airplane after ascending to the desired height.

Another object is the provision of an airship of the kind indicated having novel means to enable it to descend slowly in the event of engine failure.

A further object is the provision of an airship which may alight in water with safety.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a longitudinal vertical section of the improved airship, portions being shown in elevation.

Fig. 2 is a front view of the airship, portions of the wings being broken away.

Fig. 3 is a bottom view of the airship, portions of the wings being broken off.

The airship has a large open ended cylindrical body composed of the outer and inner shells 1 and 2, and the space between them may be used for passengers, baggage and freight.

A pilot cabin 6 depends from the rear portion of the outer shell 1 with the body in horizontal position, as seen in Fig. 1, and the shell 1 has a longitudinal keel 7 extending from the cabin 6 to the forward end of the body.

Wings 5 extend from the opposite sides of the body to prevent rotation of the body during vertical ascent, and to enable the machine to glide in the air like an airplane, when in flight as seen in Fig. 1.

Vertical and horizontal rudders 3 and 4, respectively, are hingedly mounted at the rear end of the body, and are suitably controlled by any well known means. As

shown, the control includes a lever 13 within the cabin 6 connected to the rudder 4, and the same or other lever may control the rudder 3, as well known in the art.

A longitudinal axial shaft 10 is journaled in cross bars 8 mounted within the body, and said shaft is driven by an engine 9 at the rear end of the body. The shaft 10 has a propeller 11 thereon within the forward end portion of the body, for drawing the air into the body and forcing it rearwardly through said body for lifting or propelling the airship.

Shock absorbing plungers or feet 15 are slidably in the tubes or cylinders 15' within the rear end of the body, for supporting the airship in vertical position on the ground, or cushioning the airship when it lands.

The pilot's seat 16 is hingedly suspended in the cabin 6 so that the seat will remain in the same position when the airship is in vertical and horizontal positions. In horizontal flight the pilot is seated with his back to the rear end of the cabin 6, and in vertical ascent or descent the pilot is seated with his back toward the shell 2.

Suitable parachutes 17' are nested within the pockets 17 provided in the forward end of the body, in order that said parachutes may be released in case of necessity for a forced landing. These parachutes may be of the usual kind to suspend the airship therefrom for slow descent.

An umbrella type of parachute 18 is mounted on the shaft 10 behind the propeller, so as to be opened up during descent of the airship, to catch the air which passes through the body, so as to slow down the descent, with or without the parachutes 17'.

A propeller 18 is disposed in rear of the cabin 6, to be driven from the engine 9, for propelling the airship when it alights in water, the cabin 6 serving as a boat hull in order that the airship may travel on the surface of the water.

To make an ascent, the airship is disposed on end, as seen in Fig. 3, with the plungers or feet 15 resting on the ground. The propeller 11 being operated will lift the airship, and the wings 5 will prevent the body from

rotating. When the airship has reached a desired altitude it may be brought to a horizontal position, as seen in Fig. 1, by controlling the rudder 4. The airship may then be steered by the rudders 3 and 4 and will have a flight similar to an airplane, the wings 5 sustaining the heavier rear portion of the airship while the propeller 11 draws the forward end of the body forwardly and sustains it in flight.

Should the engine fail or other contingency arise, the rear heavier portion of the airship will fall faster than the forward end, and the air rushing up through the body 15 will open the parachute 18, and thereby slow down the descent. The parachutes 17 may also be released.

The airship, after horizontal flight, may also be turned to vertical position and the 20 propeller 11 slowed down in order that vertical descent may be made, the airship landing on the plungers 15 which are cushioned to absorb the shock.

The airship may descend on the surface of 25 water, and will float, the shells 1 and 2 and cabin 6 being of water-tight construction, and may be provided with suitable windows for observation. The propeller 19 enables the airship to be propelled in the water.

30 Having thus described the invention, what is claimed as new is:

1. An airship comprising an open-ended tubular body, a propeller within said body, a cabin depending from the body at the rear 25 end thereof, and a keel depending from the body in front of the cabin.

2. An airship comprising an open-ended tubular body, a propeller within the passage of said body, said body having provisions 40 at one side including a keel to move in water with the body horizontal, a water propeller associated with said provisions, and rudders disposed across one open end of the body.

3. An airship comprising an open-ended 45 cylindrical body, a propeller mounted in the forward open end of the body, an engine mounted in the rear open end of the body and connected to said propeller, and rudders mounted across the rear open end of the body.

50 4. An airship according to claim 3, and including a folded parachute immediately behind the propeller and adapted to be opened up within the body.

55 5. An airship according to claim 3 and including an umbrella type parachute mounted immediately behind the propeller to be opened up within the body.

60 6. An airship according to claim 3, and including wings extending from the body near the rear end thereof.

7. An airship according to claim 3, wherein the body has a cabin projecting therefrom near the rear end of the body and adapted to float in water.

8. An airship according to claim 3 including a cabin projecting from the body near the rear end thereof and adapted to float in water, and a water propeller carried by said cabin.

9. An airship according to claim 3, wherein the body has outer and inner surfaces, and including shock absorbing plungers slidably mounted in the rear end portion of the body between the outer and inner surfaces thereof.

10. An airship comprising an open ended cylindrical body, propelling means located within the forward open end of the body, an engine mounted in the body in rear of and connected to said propelling means, and rudders carried by the body at the rear end thereof, the body having a cabin projecting therefrom near the rear end of the body and adapted to float in water.

11. An airship according to claim 10, and a keel projecting from the body in front of said cabin.

12. An airship according to claim 10, and a water propeller carried by said cabin.

13. An airship comprising an open ended cylindrical body, propelling means located within the forward open end of the body, an engine mounted in the body in rear of and connected to said propelling means, rudders carried by the body at the rear and thereof, and shock absorbing plungers slidably mounted in the rear end portion of the body between the outer and inner surfaces thereof.

14. An airship comprising an open ended cylindrical body, propelling means located within the forward open end of the body, an engine mounted in the body in rear of and connected to said propelling means, and rudders carried by the body at the rear end thereof, the forward end of the body having 10 parachute pockets between the outer and inner surfaces of the body.

In testimony whereof I have signed my name to this specification.
